(57) **CLAIM**

We claim the ornamental design for an elevated planter, as shown and described.

DESCRIPTION

FIG. 1 is an isometric view of a first embodiment of an elevated planter showing the claimed design;

FIG. 2 is a front view thereof;

FIG. 3 is a rear view thereof;

FIG. 4 is a right side view thereof;

FIG. 5 is a top view thereof;

FIG. 6 is an isometric view of a second embodiment of an elevated planter; and,

FIG. 7 is a top view thereof.

The front, rear, right and left views of the second embodiment of the design are identical to the front, rear, right and left views of the first embodiment.
